CIRCUIT INTERRUPTING APPARATUS

Hugh A. Triplett, Wilmette, Ill., assignor to
Schweitzer & Conrad, Inc., Chicago, Ill., a cor-
poration of Delaware

Application October 19, 1936, Serial No. 106,422

40 Claims. (Cl. 200—117)

My invention relates generally to electric circuit interrupters and it has particular relation to fuses.

It is now well known to those skilled in the art that an arc drawn between the separable terminals of a circuit interrupter within a body of arc extinguishing material, such as magnesium hydroxide or boric acid, may be extinguished by the gases which are evolved from this material by the heat of the arc. Circuit interrupters have been constructed in which the arc extinguishing material is provided with two longitudinal bores, one a main and centrally located bore and the other an auxiliary bore of smaller diameter than and positioned parallel to the main bore. An arcing terminal is provided in the main bore which may be retracted from the adjacent end terminal of the circuit interrupter or fuse by a spring when the fusible element connecting these terminals melts. If the current is relatively small, an arc is established in the auxiliary bore where a conductor is positioned having one end connected to the arcing terminal and the other end disposed in such relation to the adjacent end terminal as to form a small gap therebetween. This gap is broken down on blowing of the fusible member or element and, as a result, the arc is extinguished in the auxiliary bore rather than in the main bore.

In a circuit interrupter of this type the main bore is so proportioned that, under short circuit conditions when a relatively large flow of current takes place, the pressure due to the arc contacting and vaporizing the arc extinguishing material will not rupture the fuse container. When the short circuit interrupting requirements are met in such a device, prompt circuit interruption is not obtained in the main bore when the fault current is relatively small. This is due to the fact that the relatively feeble arc does not make sufficient contact with the arc extinguishing material to release the required quantity of gas to deionize the arc stream at current zero. If the current causing the fusible element to melt is relatively great, such as that which flows on short circuit, an arc will persist in the main bore. It will be extinguished in the main bore by lengthening its path in this bore and by ample evolution of gases from the arc extinguishing material. In my copending application, Serial No. 85,700, filed June 17, 1936, and assigned to the assignee of this application, I have disclosed a circuit interrupter of the type described in which an arcing terminal is withdrawn in a main bore in a mem- ber formed of solid arc extinguishing material,

the arcing terminal being held against the biasing force of the spring by a strain wire that is positioned in the auxiliary bore of the solid arc extinguishing material. When the main fusible element, which is connected between the arcing terminal and the adjacent end terminal, melts because of a fault in the circuit, the entire flow of current is transferred to the strain wire in the small bore. If the current flowing as a result of the fault is relatively small, the arc formed thereby will be readily extinguished in the small bore. If the current in the arc that is required to be interrupted exceeds the capacity of the auxiliary bore, the arc will restrike in the main bore and will be there extinguished because of the inherent capability of this bore for extinguishing large current arcs. In a device of this character it is essential to provide some means for extinguishing low current arcs which cannot be effectively extinguished in the main bore. In my copending application this problem has been solved by positioning the strain wire in the auxiliary bore where the small current arcs are readily interrupted because of its inherent capacity to interrupt such arcs.

Instead of permitting an arc to be formed and extinguished in the small bore, it may be desirable to provide for merely increasing the resistance of the shunt path after the current is shunted through it to a very high value, thereby obtaining a substantially arcless functioning of the fuse within a certain range of operation. If the current required to be interrupted is beyond this range of operation, an arc will also persist in the main bore of the arc extinguishing material where it will be extinguished in the usual manner.

A device which is inherently capable of automatically increasing its resistance to a very high value on flow of current therethrough is disclosed in my copending application, Serial No. 669,955, filed May 8, 1933, and assigned to the assignee of this application, now Patent 2,066,129. As there disclosed I have provided a variable resistive element which has the characteristic of cumulatively increasing its own resistance, not merely by the thermal coefficient of resistance which is a property of the metal employed, but by a chemical union with a reagent which is liberated by the heat generated by the element. This reaction, which produces a permanent change, reduces the element from a conductor to a non-conductor, without arriving at the stage of forming free metal vapor as a part of the current carrying path. In general, the variable re-

sistance element comprises a tungsten conductor in the form of a coil which is embedded in a powdered compound, preferably comprising calcium carbonate. On being heated the tungsten 5 wire reacts with the calcium carbonate in such manner as to be transformed from a conductor to a non-conductor. In this copending application I have disclosed this variable resistance element in combination with a circuit interrupter 10 of the liquid arc extinguishing type. The variable resistance element serves to assist the interrupter in extinguishing large current arcs, the interrupter itself being inherently capable of extinguishing small current arcs. The variable 15 resistance element is not called upon to function except in the event that the current required to be interrupted exceeds a relatively small value which can be readily interrupted by the circuit interrupter. The large fault current flowing 20 causes the tungsten conductor to be heated to such an extent that it reacts with the surrounding calcium carbonate and it changes its characteristic to that of a non-conductor, during which change the current flow in the circuit is 25 correspondingly reduced without arcing, except as an arc is formed between the relatively movable terminal members of the circuit interrupter.

It is one of the objects of my present invention to combine the operating features of the variable 30 resistance element with a circuit interrupter of the type which depends for its operation upon the blast action on an arc drawn in a restricting bore of fixed diameter and to so arrange and connect the variable resistance element that it will 35 be effective to interrupt low current faults which cannot be effectively taken care of in the large bore.

The principal object of my invention is to accomplish prompt circuit interruption at low values 40 of current which cannot be expeditiously interrupted in the main bore.

An important object of my invention is to accomplish circuit interruption without the necessity of moving parts in the shunt circuit and 45 without compromising the operation of the interrupter during short circuits.

Another important object of my invention is to provide for automatically increasing the resistance of a shunt path in a fuse of the solid arc 50 extinguishing material type whereby substantially arcless circuit interruption may be obtained within a limited range of current flow.

A specific object of my invention is to provide for connecting a refractory metal conductor 55 embedded in a powdered compound between the arcing terminal and the adjacent terminal of a fuse of the solid arc extinguishing material type to offer a path for the flow of current in the shunt circuit thus formed while the arcing terminal is being retracted by its spring, the path 60 being changed to a non-conductor by the action of the current flowing through it.

Other objects of my invention will in part be obvious and in part appear hereinafter.

65 My invention, accordingly, is disclosed in the embodiment hereof shown in the accompanying drawing and it comprises the features of construction, combination of elements and arrangement of parts which will be exemplified in the 70 construction hereinafter set forth and the scope of the application of which will be indicated in the appended claims.

For a more complete understanding of the nature and scope of my invention reference may 75 be had to the following detailed description taken

in connection with the accompanying drawing, in which:

Figures 1 and 2, taken together, show a concrete embodiment of my invention, Figure 1 illustrating one end of the fuse and Figure 2 5 illustrating the other end; and

Figure 3 is a detail cross-sectional view of a modified connection for the shunt circuit.

According to my invention the arc extinguishing material, such as magnesium hydroxide or 10 boric acid, of a circuit interrupter is provided with a single bore in which the arcing terminal moves under the influence of the tension spring. A strain wire is connected directly between the arcing end of the arcing terminal and the adjacent 15 terminal at the end of the fuse housing, while a fusible element, such as a silver wire, is connected in shunt circuit relation with the strain wire to carry the load current.

With a view to providing effective means for 20 interrupting currents of values lower than those adapted to be extinguished effectively in the main bore, the arc extinguishing material is surrounded with a filling of a powdered compound comprising calcium carbonate in which is embedded 25 a conductor in the form of a coil which may be tungsten. One end of the coil is connected electrically to the arcing terminal while the other end may either be disposed in insulated spaced relation to or electrically connected to 30 the end terminal of the interrupter adjacent the arcing terminal. When the fusible element and the strain wire are fused on the occurrence of sufficient overload to effect this operation, the slight gap between the end of the coil and the 35 adjacent fuse terminal is broken down, if the gap is used, and current flows through the tungsten coil while the arcing terminal is being withdrawn in the bore to a safe distance against restriking. If the gap is not used, then the main 40 current is immediately shunted through the coil in addition to the relatively small current already flowing therethrough. The flow of current through the tungsten coil with the resulting heating and chemical effects causes in either case 45 a rapid change of the metallic conducting path to one which is essentially non-conducting without the formation of an arc as described in my copending application, Serial No. 669,955, referred to hereinbefore.

50 In the event that the current required to be interrupted is greater than that which can be handled by the shunt conductor, an arc will persist in the main bore between the arcing terminal and the adjacent end terminal which will be extinguished in the usual manner by the evolution of gases from the arc extinguishing material. In this case the tungsten coil will be converted to a non-conductor but it will perform no useful function.

60 Referring now particularly to the drawing, it will be observed that a circuit interrupter, shown generally at 70, is provided which has the above described advantages and operating characteristics. The circuit interrupter 70 comprises a 65 housing or fuse tube 71, shown for illustrative purposes as being composed of glass, having at its upper end an upper ferrule 72 provided with upwardly extending spring fingers 73 which may be integrally formed therewith. The ferrule 72 70 may be machined from a solid brass rod and slots are milled diametrically opposite each other to provide the spring fingers 73. Since the sectional view is taken through a pair of these slots, the fingers 73 are shown in elevation. At the 75

lower end of the fuse tube 11 a lower ferrule 14 is provided having a cap 15 threaded into it, as illustrated. The cap 15 has secured thereto a spring and cable fastener 16 to which a cable 16 and a spring 17 may be connected. The cables 16 and the spring 17 have a spring and cable fastener 22 at their upper ends. The foregoing described parts of the fuse 10 form the portion thereof into which a cartridge, shown generally at 11, may be inserted to provide a fuse of the renewable element type.

It will be observed that the cartridge tube 11 comprises a cartridge tube 18 which may be fiber, but which preferably is made of fiber paper impregnated with "Bakelite" and rolled into a sleeve and cured. The tube 18 extends downwardly to provide a shield around the upper end of the spring 17. A cartridge ferrule 19 is mounted on the upper end of the cartridge tube 18 and is secured in engagement therewith by pins 80. A shoulder nut 81 is threaded on the upper end of the cartridge ferrule 19 for cooperating with the spring fingers 13 to secure the cartridge 11 in operative position and to facilitate unloading without blowing of the fusible element 93 and the strain wire 90. Inside of the cartridge tube 18 an arcing tube 82 is provided which may be formed of an arc extinguishing material such as magnesium hydroxide, boric acid or the like, and which will evolve a gas in the presence of an arc to assist in extinguishing the arc. The arcing tube 82 may be formed as a continuous tube or it may be sectioned, if desired. A single bore 83 is provided in the center of the arcing tube 82 as illustrated. The arcing tube 82 may be secured in position in the cartridge tube 18 by means of a metallic cartridge washer 84 which is fastened to the inner walls of the cartridge tube 18 by pins 85 or any other suitable means. At the upper end of the arcing tube 82 a retaining ring 86 is provided with external threads for engaging the interior threads of the cartridge ferrule 19. The retaining ring 86 is formed of an insulating material such as fiber and is provided with a frusto-conical opening, as illustrated, to provide an arcing chamber.

An arcing terminal 87, rod-like in shape and preferably formed of copper, is positioned inside of the bore 83 with a slight clearance to permit free movement and is disposed to be retracted by the spring 17 to which it is connected by the spring and cable fastener 22. The lower end of the arcing terminal 87 is threaded into the spring and cable fastener 22 as will be readily understood. In order to prevent the arcing terminal 87 from turning relative to the cartridge washer 84, its lower end is provided with a hexagonal nut 88 that is arranged to interfit with a corresponding opening in the lower surface of the cartridge washer 84. Contact with the arcing terminal 87 is maintained by means of a garter spring 89 positioned around it in a suitable groove in the cartridge washer 84. It is desirable to maintain an electrical connection between the arcing terminal 87 and the cartridge washer 84 as the former is moved through the latter for a purpose which will be apparent herein-after.

The arcing terminal 87 is held against the reactive force of the spring 17 by means of a strain wire 90 which may be looped over a transverse pin 91 in the cartridge ferrule 19 and a pin 92 that extends transversely through a slot in the upper end of the arcing terminal 87. A main fusible element or wire 93, preferably in

the form of a coil of silver wire, is connected between the upper end of the arcing terminal 87 and the cartridge ferrule 19. One end of the fusible element 93 is secured in a suitable opening in the upper end of the arcing terminal 87 which may be peened over or otherwise secured thereto while the other end is threaded through a suitable opening in the cartridge ferrule 19 and the walls of the opening are distorted, as by means of a prick punch or the like, to pinch them into good electrical contact with the upper end of the fuse wire 93.

With a view to providing a shunt path around the arc which is formed when the fusible element 93 and the strain wire 90 are melted, which shunt path may be reduced to a non-conductor by the action of the current flowing through it, a filling 94 of solid material such as a powdered compound is positioned around the arcing tube 82 and between it and the inner wall of the cartridge tube 18. The powdered compound is composed principally of calcium carbonate in the form of limestone or marble dust and it has embedded therein a conductor 95 in the form of a coil, one end of which is connected by any suitable means to the cartridge washer 84, while the other end extends through a suitable opening 96 in the cartridge ferrule 19, where it may be insulated therefrom by an insulating bushing 97. The conductor 95 is formed preferably of tungsten, although it may be formed of molybdenum, tantalum, or a similar metal of a class which has a high melting point and which, when raised to a high temperature will evolve from the compound 94 a suitable reagent and combine therewith. In its original form the resistance of the conductor 95 is relatively low. However, when it is heated to a high temperature, it will react with the powder 94 in such manner as to change its characteristics from that of a conductor to that of a non-conductor. It will now be apparent that no deterioration of the conductor 95 takes place during normal operation of the interrupter because it is insulated at its upper end from the cartridge ferrule 19. However, the gap therebetween is slight and may be readily broken down by increased voltage drop on melting of the strain wire 90 and the fusible element 93.

It will be apparent that the upper end of the conductor 95 may be so positioned with respect to the cartridge ferrule 19 as to position the gap therebetween in the path of the ionized gases that are formed on blowing of the fusible element 93 and the strain wire 90. The gap would then be more readily broken down because of the conducting path therein formed by the ionized gases.

It may be desirable to provide a metallic connection between the upper end of the conductor 95 and the cartridge ferrule 19, thereby providing a permanent metallic shunt path around the strain wire 90 and the fusible element 93. For this purpose a metallic bushing 97' may be employed, as shown in Figure 3, and positioned in the opening 96. The bushing 97' may be formed of a suitable conducting material, such as copper or brass, and it may be swaged about the conductor 95 and driven into the opening 96 to provide good electrical contact with the cartridge ferrule 19. In this embodiment of the invention the conductor 95 carries a slight amount of current during normal operation but this current is not sufficient to change its resistance. It is only after the fusible element 93 and the strain wire 90 are fused, that sufficient current 75

flows through the conductor 95 to change its resistance characteristics.

5 A cross pin 98 is positioned across the cartridge ferrule 79 to provide for engagement with a suitable tool for drawing the cartridge 77 through the fuse tube 71 and placing it in the operative position as shown in the drawing.

The cartridge 77 may be connected to the spring 17 and the cables 16 by screwing the arcing terminal 87 into the upper cable fastener 22. The assembly may then be positioned in the fuse tube 71 and the cap 76 may be screwed into place. A suitable tool, somewhat in the form of a button hook, is inserted through the other end 15 of the fuse tube 71 to engage the pin 98 and draw up the cartridge 77 to the position illustrated in the drawing. In this position the shoulder nut 81 is in engagement with the upper ends of the spring fingers 73 and the cartridge 77 is thereby prevented from moving inwardly under the influence of the tension spring 17. A clamp nut 99 may then be screwed onto the threaded portions of the spring fingers 73 for locking them in position. It will be observed that the clamp 20 nut 99 is provided with an internal tapered clutch surface which, when drawn tight on the threads, forces the spring finger 73 radially inwardly to engage the cartridge ferrule 79 with a clutching action and provide a good electrical connection 25 between the fusible element 93 and the upper ferrule 72.

In operation, when a predetermined overload occurs in a circuit in which the interrupter 70 shown in Figures 1 and 2 is connected, the fusible 30 element 93 melts and shunts the current to the strain wire 80, which also melts, thereby releasing the arcing terminal 87 for movement under the influence of spring 17. An arc is then formed between the cartridge ferrule 79 and the 35 arcing terminal 87, as the latter is retracted within the bore 83 of the arcing tube 82. A sufficient voltage will then be impressed, following the first current zero of arcing, between the cartridge ferrule 79 and the upper end of the 40 conductor 95 to break down the gap formed by the insulation bushing 97 and consequently current will flow through the conductor 95. Since the conducting path through the conductor 95 will now be of relatively low resistance, the arc 45 will not persist in the bore 83. The current flow, now shunted through the conductor 95, will heat it to a sufficiently high temperature to cause re-action with the powdered compound 84 and change its characteristics to those of a non-con- 50 ductor.

Meanwhile the arcing terminal 87 in the bore 55 has been withdrawn to a safe distance against restriking by the spring 17 and interruption has been accomplished without arcing except for the initial arc formed by the fusion of the fusible element 93 and the strain wire 80. Because of the provision of the garter spring 89 in the cartridge washer 84, the lower end of the coil 85 is maintained in continuous conducting engagement 60 with the arcing terminal 87. This insures a complete conducting path between the ferrules 72 and 74 through the conductor 95 for the low current interrupting condition.

If the interrupter 70 is called upon to interrupt 65 an overload approaching a short circuit, the arc will persist in the bore 83, where it will be extinguished by the lengthening of its path and the gas which is evolved from the arcing tube 82.

When the construction shown in Figure 3 is 70 used in conjunction with the remaining parts

of the interrupter 70, illustrated in Figures 1 and 2, the entire current immediately flows through the conductor 95 on melting of the fusible element 93 and the strain wire 80 and no arc is formed in the bore 83, since the gap is not present and the conductor 95 forms a part of a metallic circuit shunting the fusible element 93 and the strain wire 80. The conductor 95 then loses its conducting qualities and changes, as described hereinbefore, to have the characteristics of a non-conductor. For low fault currents, this construction provides arcless circuit interruption.

If desired, the fuse tube 71 may be of such a length that the arcing terminal 87 will be completely withdrawn from the arcing tube 82 and moved out of contact engagement with the garter spring 89 and the cartridge washer 84. This operation may be desired for the purpose of completely insulating the ferrule 74 from the ferrule 72 after the fuse has operated on a low current fault. After the interrupter 70 has operated, the resistances of the auxiliary circuit and of the surface of the bore 83 are very high but a complete withdrawal of the terminal 87 from the washer 84 insures increased protection against reestablishment of a conducting path along the surface of tube 78.

After the fuse device 70 has operated to interrupt the circuit, the cartridge 77 may be removed and replaced with a new one of suitable current carrying capacity. The fuse device 70 will then be capable of again interrupting the circuit in the manner herein set forth on the occurrence of an overload condition.

The fuse device 70 has been shown and described with the arcing terminal 87 located at the upper end. It will be obvious that the position of the fuse device 70 may be reversed and that the circuit would then be interrupted at the lower end. This is the preferred position for mounting the fuse device 70 for operation. However, for purposes of illustration, it has been shown in the up and down position.

Since certain further changes may be made in the foregoing constructions and different embodiments of the invention may be made without departing from the scope thereof, it will be understood that all matter shown in the accompanying drawing or described hereinbefore shall be interpreted as illustrative, and not in a limiting sense.

I claim as my invention:

1. The combination, with a circuit interrupter depending for its operation upon the blast action on an arc drawn in a restricting bore formed in a solid arc extinguishing material, of a circuit in parallel with said circuit interrupter for interrupting currents smaller than the currents readily interrupted in said bore, said parallel circuit including a conductor the resistance of which increases to a relatively high value by the action of the current flowing through it.

2. The combination, with a circuit interrupter depending for its operation upon the blast action on an arc drawn in a restricting bore formed in a solid arc extinguishing material, of a circuit in parallel with said circuit interrupter for interrupting currents smaller than the currents readily interrupted in said bore, said parallel circuit comprising a metallic conductor arranged and adapted to increase its resistance rapidly and to be converted to a non-conductor by the action of the current flowing through it.

3. The combination, with a circuit interrupter depending for its functioning upon the blast

action on an arc drawn in a restricting bore formed in a solid arc extinguishing material from which gases are evolved by the heat of the arc, of a parallel circuit around said circuit interrupter 5 for interrupting currents smaller than the currents readily interrupted in said bore by said blast action, said parallel circuit including a conductor the resistance of which increases to a relatively high value by the action of the current 10 flowing through it, and means preventing current flow through said conductor during normal operation.

4. The combination, with a circuit interrupter depending for its functioning upon the blast 15 action on an arc drawn in a restricting bore formed in a solid arc extinguishing material from which gases are evolved by the heat of the arc, of a parallel circuit around said circuit interrupter for interrupting currents smaller than the 20 currents readily interrupted in said bore by said blast action, said parallel circuit including a conductor the resistance of which increases to a relatively high value by the action of the current flowing through it, and means including an arc 25 gap connected in series with said conductor for preventing current flow therethrough during normal operation.

5. The combination, with a circuit interrupter depending for its functioning upon the blast 30 action on an arc drawn in a restricting bore formed in a solid arc extinguishing material from which gases are evolved by the heat of the arc, of a parallel circuit around said circuit interrupter for interrupting currents smaller than the 35 currents readily interrupted in said bore by said blast action, said parallel circuit comprising a metallic conductor arranged and adapted to rapidly increase its resistance and to be converted without fusing to a non-conductor by the action 40 of the current flowing through it, and means including an arc gap connected in series with said conductor for preventing current flow therethrough during normal operation.

6. In a circuit interrupter, in combination; a 45 first interrupting means arranged and adapted to interrupt large currents and comprising a tube formed of solid arc extinguishing material and a rod-like terminal member movably mounted in the bore of said tube, current interruption being 50 effected by a free flow toward the open end of said bore of gases evolved from its inner wall by the action of the arc thereon; and a second interrupting means arranged and adapted to interrupt small currents, in parallel with said first 55 interrupting means and comprising a metallic conductor embedded in a mass of insulating material, current interruption in said second interrupting means being effected on conversion of said metallic conductor to a non-conductor by 60 reaction therewith of said insulating material caused by heat generated by current flow through said conductor.

7. In a circuit interrupter, in combination; a first interrupting means arranged and adapted to 65 interrupt large currents and comprising a tube formed of solid arc extinguishing material and a rod-like terminal member movably mounted in the bore of said tube, current interruption being effected by a free flow toward the open end of said 70 bore of gases evolved from its inner wall by the action of the arc thereon; a second interrupting means arranged and adapted to interrupt small currents, in parallel with said first interrupting means and comprising a metallic conductor embedded in a mass of insulating material, current 75

interruption in said second interrupting means being effected on conversion of said metallic conductor to a non-conductor by reaction therewith of said insulating material caused by heat generated by current flow through said conductor; and means preventing current flow through said second interrupting means while normal load current flows through said first interrupting means. 5

8. In a circuit interrupter, in combination; a first interrupting means arranged and adapted to 10 interrupt large currents and comprising a tube formed of solid arc extinguishing material and a rod-like terminal member movably mounted in the bore of said tube, current interruptions being effected by a free flow toward the open end of 15 said bore of gases evolved from its inner wall by the action of the arc thereon; a second interrupting means arranged and adapted to interrupt small currents, in parallel with said first interrupting means and comprising a metallic conductor embedded in a mass of insulating material, and an arc gap connected in series with said conductor to prevent current flow therethrough while normal load current flows through said first interrupting means, current interruption in said 20 second interrupting means being effected by breaking down of said arc gap on operation of said first interrupting means and conversion of said metallic conductor to a non-conductor by 25 reaction therewith of said insulating material caused by heat generated by current flow through said conductor.

9. In a circuit interrupter, in combination, a main fusible element of silver normally out of contact with surrounding materials and arranged 30 and adapted to fuse upon overload of a predetermined value causing the interrupter to operate, means dependent upon the blast action of gases evolved from a solid arc extinguishing material and disposed to extinguish arcs of large current 35 value formed by fusing of said silver element but not arcs of low current value, an auxiliary element of tungsten disposed to shunt said silver element and normally closely surrounded by an insulating material, said tungsten element on increased flow of current therethrough being converted to a non-conductor by chemical action 40 with said surrounding material for interrupting overloads of low value. 45

10. In a circuit interrupter, in combination, a first interrupting means arranged and adapted by its calibration to control the operation of the interrupter, and to effectively extinguish large 50 overload arcs and being relatively ineffective to extinguish small overload arcs, a second interrupting means disposed to be connected in shunt with said first interrupting means and comprising a metallic circuit closely embedded in an insulating material and arranged and adapted to react therewith, to prevent the formation of appreciable arcs by low overloads in said first interrupting means and to interrupt these low overload arcs effectively after the operation of said first interrupting means. 55

11. A circuit interrupter comprising, in combination, a housing having fixed terminals, a tension spring in one end of said housing, a body of solid arc extinguishing material in the other end of said housing provided with a longitudinal bore, an arcing terminal in said bore disposed to 60 be retracted by said spring, fusible means connecting said arcing terminal and the adjacent fixed terminal, and chemical fuse means disposed to be connected between said arcing and adjacent terminals when said fusible means melts. 70 75

12. A circuit interrupter comprising, in combination, a housing having fixed terminals, a tension spring in one end of said housing, a body of solid arc extinguishing material in the other end of said housing provided with a longitudinal bore, an arcing terminal in said bore disposed to be retracted by said spring, a main fusible element connecting said arcing terminal and the adjacent fixed terminal, a strain wire for holding 5 said arcing terminal against the force of said spring, and a chemical fuse element the resistance of which increases to a relatively high value on being heated to a predetermined temperature arranged and adapted to be connected between 10 said arcing and adjacent terminals when said main fusible element blows.

13. A circuit interrupter comprising, in combination, a housing having fixed terminals, a tension spring in one end of said housing, a body 20 of solid arc extinguishing material in the other end of said housing provided with a longitudinal bore, an arcing terminal in said bore disposed to be retracted by said spring, main fusible means connecting said arcing terminal and the adjacent fixed terminal, and a chemical fuse element 25 disposed to be connected between said arcing and adjacent terminals when said main fusible means melts, said chemical fuse element comprising a conductor and an associated reagent for reacting therewith to become substantially non-conductive on being heated to a temperature sufficient to initiate a reaction.

14. A circuit interrupter comprising, in combination, a housing having fixed terminals, a tension spring in one end of said housing, a body 30 of solid arc extinguishing material in the other end of said housing provided with a longitudinal bore, an arcing terminal in said bore disposed to be retracted by said spring, a main fusible element 35 connecting said arcing terminal and the adjacent fixed terminal, a strain wire for holding said arcing terminal against the retractile force of said spring, and a chemical fuse element arranged and adapted to be connected between 40 said arcing and adjacent terminals when said main fusible element and strain wire melt, said chemical fuse element comprising a conductor and an associated reagent for reacting therewith to become substantially non-conductive on being 45 heated to a temperature sufficient to initiate a reaction.

15. A circuit interrupter comprising, in combination, a housing having fixed terminals, a tension spring in one end of said housing, a body of solid arc extinguishing material in the other end of said housing provided with a longitudinal bore, an arcing terminal in said bore disposed to be 50 retracted by said spring, a main fusible element connecting said arcing terminal and the adjacent fixed terminal, and a chemical fuse element disposed to be connected between said arcing and adjacent terminals when said main fusible element blows, said chemical fuse element comprising a powdered compound surrounding said body 55 of arc extinguishing material and a conductor of refractory metal embedded therein, said conductor reacting with said compound to become substantially non-conductive on being heated to a temperature sufficient to initiate the reaction.

16. A circuit interrupter comprising, in combination, a housing having fixed terminals, a tension spring in one end of said housing, a body of solid arc extinguishing material in the other end of said housing provided with a longitudinal bore, an arcing terminal in said bore disposed to be 60

retracted by said spring, a main fusible element connecting said arcing terminal and the adjacent fixed terminal, a powdered compound surrounding said body of arc extinguishing material, and a coil of refractory metal embedded in 5 said compound, one end of said coil being connected to said arcing terminal and the other end being disposed in insulated spaced relation to said adjacent fixed terminal.

17. In a circuit interrupter, in combination, a first interrupting means arranged and adapted by its calibration to control the operation of the interrupter, and to effectively extinguish large overload arcs by the blast action of gases formed by the action of these arcs upon a solid arc extinguishing material and being relatively ineffective to extinguish small overload arcs, a second interrupting means disposed to be connected in shunt with said first interrupting means and comprising a metallic circuit closely embedded 15 in an insulating material and arranged and adapted to react therewith to prevent the formation of appreciable arcs by low overloads in said first interrupting means and to interrupt these low overload arcs effectively after the operation 20 of said first interrupting means.

18. A circuit interrupter comprising, in combination, a housing having fixed terminals, a tension spring in one end of said housing, a body of solid arc extinguishing material in the other 30 end of said housing provided with a longitudinal bore, an arcing terminal in said bore disposed to be retracted by said spring, a main fusible element connecting said arcing terminal and the adjacent fixed terminal, a powdered compound 35 surrounding said body of arc extinguishing material, and a coil of refractory metal embedded in said compound and interconnected between said arcing terminal and said adjacent fixed terminal.

19. A circuit interrupter comprising, in combination, a pair of spaced apart terminal members for connection in an electric circuit, a fusible element interconnecting said terminal members, a member of solid arc extinguishing material having a bore therein, means for moving 45 one of said terminal members through said bore on melting of said fusible element, and a variable resistance element arranged and adapted to be connected between said terminal members when said fusible element melts, the resistance 50 of said variable resistance element increasing to a relatively high value as a function of current flow therethrough.

20. A circuit interrupter comprising, in combination, a pair of spaced apart terminal members for connection in an electric circuit, a fusible element interconnecting said terminal members, a member of solid arc extinguishing material having a bore therein, means for moving one 55 of said terminal members through said bore on melting of said fusible element, and auxiliary circuit means paralleling said fusible element and conducting current between said terminal members when said fusible element melts, said auxiliary circuit means including a conductor of 60 refractory metal embedded in a powdered compound, said conductor reacting with said compound to become substantially non-conductive 65 on being heated by current flow therethrough to a temperature sufficient to initiate the reaction. 70

21. A circuit interrupter comprising, in combination, a pair of spaced apart terminal members for connection in an electric circuit, a fusible element interconnecting said terminal members, a member of solid arc extinguishing mate- 75

rial having a bore therein, means for moving one of said terminal members through said bore on melting of said fusible element, a conductor composed of tungsten paralleling said fusible element and conducting current between said terminal members when said fusible element melts, and a filling of calcium carbonate surrounding said conductor, the tungsten of said conductor reacting with said calcium carbonate to render 10 said conductor substantially non-conductive when it is heated to a temperature sufficient to initiate the reaction by current flow therethrough.

22. The method of interrupting a relatively low current in a circuit interrupter inherently capable of effectively interrupting large currents which comprises shunting the entire current through an auxiliary circuit and automatically increasing the resistance of said auxiliary circuit to a relatively high value as a function of the current 20 flow therethrough.

23. The method of interrupting current flow in a circuit in which a circuit interrupter is connected that is capable of interrupting arcs caused by large current flow in said circuit but 25 not arcs caused by small current flow which comprises opening the circuit interrupter, shunting the small current through an auxiliary circuit, and automatically increasing the resistance of the auxiliary circuit to a relatively high value as 30 a function of the current flow therethrough.

24. In a circuit interrupter, in combination; a first interrupting means arranged and adapted to interrupt large currents and comprising a tube formed of insulating material and a rod-like 35 terminal member movably mounted in the bore of said tube, current interruption being effected by a free flow toward the open end of said bore of gases evolved from its inner wall by the action of the arc thereon; and a second interrupting means arranged and adapted to interrupt small currents, connected in parallel with 40 said first interrupting means and comprising a metallic conductor embedded in the wall of a tube of insulating material, current interruption 45 in said second interrupting means being effected on conversion of said metallic conductor to a non-conductor by reaction therewith of said insulating material caused by heat generated by current flow through said conductor, said tube 50 of insulating material being positioned around said bore and separating it from said second interrupting means whereby the arc drawn in said bore does not affect the functioning of said metallic conductor.

25. In a circuit interrupter, in combination; a first interrupting means arranged and adapted to interrupt large currents and comprising a tube formed of insulating material and a rod-like terminal member movably mounted in the bore of 55 said tube, current interruption being effected by a free flow toward the open end of said bore of gases evolved from its inner wall by the action of the arc thereon; a second interrupting means arranged and adapted to interrupt small currents, connected in parallel with said first interrupting means and comprising a metallic conductor embedded in the wall of a tube of insulating material, current interruption in said second interrupting means being effected on conversion of 60 said metallic conductor to a non-conductor by reaction therewith of said insulating material caused by heat generated by current flow through said conductor, and means for completely withdrawing said rod-like terminal member from said bore after the circuit is in- 65

terrupted whereby the likelihood of an arc re-striking through either of said circuit interrupters is reduced to a minimum.

26. A refill unit for a circuit interrupter, including a sleeve of insulation having terminal members at the ends thereof and a tension spring disposed at one end, fastened at one end to the adjacent terminal member and provided with a coupling at the other end, comprising, in combination; a first interrupting means arranged and 5 adapted to interrupt large currents and comprising a tube of solid arc extinguishing material and a rod-like terminal member movable in the bore of said tube, current interruption being effected by a free flow toward the open end of said 10 bore of gases evolved from its inner wall by the action of the arc thereon; and a second interrupting means arranged and adapted to interrupt small currents, connected in parallel with 15 said first interrupting means and comprising a metallic conductor embedded in a tubular mass of insulating material disposed around said tube of solid arc extinguishing material, current interruption being effected on conversion of said metallic conductor to a non-conductor by re- 20 action therewith of said insulating material caused by heat generated by current flow through said conductor; both said interrupting means being adapted to be positioned in the other end of said sleeve, and one end of said rod-like terminal member being adapted to be readily connected to said coupling and the other end being connected by a fusible element to the adjacent end terminal member.

27. A refill unit for a circuit interrupter, including a sleeve of insulation having terminal members at the ends thereof and a tension spring disposed at one end, fastened at one end to the adjacent end terminal member and having a threaded coupling at its other end, comprising, in 35 combination, a fiber tube disposed to be positioned in the other end of said sleeve, a tube of solid arc extinguishing material in said fiber tube, a rod-like terminal member movable in the bore of said tube of solid arc extinguishing material and threaded at its inner end for connection to said threaded coupling, fusible means at the other end of said rod-like terminal member, an annular layer of insulating material between said tubes, a conductor in the form of a 40 coil embedded in said layer and adapted to react therewith and to increase its resistance on being heated by flow of current therethrough, an annular terminal member at the outer end of 45 said fiber tube to permit clamping to the adjacent end terminal member of said sleeve, and an intermediate terminal member at the inner end of 50 said tube of arc extinguishing material, the circuits through said fusible means and said coil being connected in parallel between said annular and intermediate terminal members.

28. The combination, in a circuit interrupter depending for its operation upon the blast action on an arc drawn in a restricting bore of fixed diameter, of a rod-like terminal member movable in said bore, means for withdrawing said terminal member, and means for maintaining contact engagement with said terminal member during a predetermined portion of its movement through said bore.

29. In a fuse, in combination, a first solid arc extinguishing material adapted to assist in interrupting large overload currents by blast action on an arc drawn in a bore therein, and a second solid arc extinguishing material adapted 75

- to assist in interrupting small overload currents by chemical action on a metallic conductor closely embedded therein.
30. In a fuse, in combination, a first solid arc extinguishing material adapted to interrupt current flow by blast action on an arc drawn in a bore therein, and a second solid arc extinguishing material adapted to interrupt current flow by chemical action on a metallic conductor embedded therein.
31. In a fuse, in combination, a first solid arc extinguishing material generally tubular in form and adapted to interrupt current flow by blast action on an arc drawn in the bore thereof, and a second solid arc extinguishing material concentrically disposed with respect to said first solid arc extinguishing material and adapted to interrupt current flow by chemical action on a metallic conductor embedded therein.
32. In a fuse having a terminal adapted to be moved away from another terminal on blowing of the fuse, in combination, a first means arranged and adapted to evolve an arc extinguishing medium by the heat of an arc drawn between said terminals, a second means in parallel with said first means and arranged and adapted to interrupt current flow by increasing its resistance as a result of chemical reaction, and means for maintaining circuit connection between said second means and the movable terminal while it is moving away from the stationary terminal.
33. In a fuse having a terminal adapted to be moved away from another terminal on blowing of the fuse, in combination, a first means arranged and adapted to evolve an arc extinguishing medium by the heat of an arc drawn between said terminals, a second means in parallel with said first means and arranged and adapted to interrupt current flow by increasing its resistance as a result of chemical reaction, and means for maintaining circuit connection between said second means and the movable terminal while it is moving away from the stationary terminal, said movable terminal being completely withdrawn from said last named means in the retracted position.
34. In a fuse having a rod-like terminal adapted to be moved through a bore in a body of solid arc extinguishing material, in combination, an apertured metal member through which the rod-like terminal is withdrawn, means for maintaining electrical connection between said metal member and said terminal while the latter is being withdrawn, and means providing longitudinal movement of said terminal relative to said metal member and preventing relative rotary motion during at least a portion of said longitudinal movement.
35. In a fuse having a rod-like terminal adapted to be moved through a bore in a body of solid arc extinguishing material, in combination, a metal ring through which the rod-like terminal is withdrawn, means for maintaining electrical connection between said metal ring and said terminal while the latter is being withdrawn, and means providing longitudinal movement of said terminal relative to said metal ring and preventing relative rotary motion during at least a portion of said longitudinal movement.
36. The combination, in a circuit interrupter depending for its operation upon the blast action on an arc drawn in a restricting bore of fixed diameter, of a rod-like terminal member movable in said bore, an apertured metal member through which said terminal member is withdrawn, means for withdrawing said terminal member, and resilient means interposed between said terminal member and said metal member to maintain a circuit connection therebetween while said terminal member is being withdrawn.
37. In a fuse, in combination, a first solid arc extinguishing material having a bore and adapted to have water vapor evolved from the surface of said bore due to heat of an arc drawn therein for interrupting current flow, and a second solid arc extinguishing material cooperating with a metallic conductor embedded therein for also interrupting current flow.
38. In a fuse device, in combination, a tubular casing of insulating material having terminals at its ends, conductor means interconnecting said terminals having at least two sections one of which is adapted to blow before the other on the occurrence of an overload to interrupt the circuit between said terminals, a member biased for movement lengthwise of said housing, a strain element restraining said member and adapted to be released on blowing of one of said sections for releasing said member, and a body of solid arc extinguishing material individual to each of said sections and disposed within said casing in side-by-side relation.
39. In a fuse device of the dry type, in combination, a tubular casing of insulating material having terminals at its ends, conductor means interconnecting said terminals having at least two sections one of which is adapted to blow before the other on the occurrence of an overload to interrupt the circuit between said terminals, a plunger biased for movement lengthwise of said housing, a strain element restraining said plunger and adapted to be released on blowing of said one section for releasing said plunger, and a body of solid arc extinguishing material individual to each of said sections and disposed within said casing in side-by-side relation, one of the bodies of solid arc extinguishing material at least being formed by a granular material.
40. In a fuse device, in combination, a tubular casing of insulating material having terminals at its ends, a plurality of coextensive bodies of solid arc extinguishing material within said housing at least one of which comprises arc extinguishing material in granular form, conductor means interconnecting said terminals having at least two sections each individual to one of said bodies of arc extinguishing material and one of which blows before the other on the occurrence of an overload to interrupt the circuit between said terminals, a member movable lengthwise of said housing, spring means biasing said member to effect movement thereof, and a strain element restraining said member and adapted to be released on blowing of said one section.

HUGH A. TRIPPLETT.
